(57) **CLAIM**

The ornamental design for an agricultural machine, as
shown and described.

DESCRIPTION

FIG. 1 is a perspective view of an agricultural machine with
tool support wings, each in an unfolded position;

FIG. 2 is a left side elevational view of the agricultural
machine as in FIG. 1;

FIG. 3 is a right side elevational view of the agricultural
machine as in FIG. 1;

FIG. 4 is a front elevational view of the agricultural machine
as in FIG. 1;

FIG. 5 is a rear elevational view of the agricultural machine
as in FIG. 1;

FIG. 6 is a top plan view of the agricultural machine as in
FIG. 1;

FIG. 7 is a bottom plan view of the agricultural machine as
in FIG. 1;

FIG. 8 is a perspective view of the agricultural machine, as
in FIG. 1, with the tool support wings each in a folded
position and with a ladder, support platform and rails
removed;

FIG. 9 is a left side elevational view of the agricultural
machine as in FIG. 8;

FIG. 10 is a right side elevational view of the agricultural
machine as in FIG. 8;

FIG. 11 is a front plan view of the agricultural machine as
in FIG. 8;

FIG. 12 is a rear elevational view of the agricultural machine
as in FIG. 8;

FIG. 13 is a top plan view of the agricultural machine as in
FIG. 8; and,

FIG. 14 is a bottom plan view of the agricultural machine as
in FIG. 8.
